UNITED STATES PATENT OFFICE

JOHN W. LONEY, OF BROCKTON, MASSACHUSETTS, ASSIGNOR TO O. A. MILLER TREEING
MACHINE COMPANY, OF PORTLAND, MAINE, A CORPORATION OF MAINE

SHOE STRETCHER

Application filed May 29, 1928. Serial No. 281,456.

This invention relates to shoe stretchers. Difficulty has been experienced with devices of this kind, in locating and holding the stretching elements at those parts of the shoe where their stretching action is desired, the devices in use heretofore, so far as known, consisting merely of an expansible fore part which is liable to slip backward from a smaller to a larger portion of the shoe when it is expanded. It is an important object of my invention to provide a strong convenient and cheap stretcher in which the expansible fore part can be definitely located where desired in the shoe and maintained in this location. The illustrated stretcher has a heel member and the invention provides a strong and efficient means for expanding the fore part and preserving the distance between the heel part and fore part. In the disclosed stretcher each half of the expansible fore part is hung on a pair of toggle links the power-operated ends of which are moved toward each other at equal velocities by a right and left handed screw arrangement, which holds their points of connection to the fore part members longitudinally immovable in the shoe.

In accordance with a further feature of the invention, the illustrated stretcher may have applied interchangeably thereto each of a plurality of devices by the use of which the stretcher is caused to apply to the shoe upper a localized pressure of considerable amount. As herein illustrated, the devices referred to are in the form of sleeves, each of which may be slipped over the fore part of the stretcher, one such device being adapted to cause the stretcher to exert pressure so localized as to raise a depressed toe box, and another such device being adapted to exert localized outward pressure on the vamp of the shoe upper at the rear of the toe box. The devices referred to are designed to be slipped over the fore part of the stretcher when the fore part is closed, that is, not expanded, and the desired localized pressure may be effected merely by forcing the closed fore part of the stretcher having the device thereon into the fore part of the shoe.

These and other features of the invention

comprising certain combinations and arrangements of parts will be apparent from the following description of a preferred embodiment of the invention shown in the drawings, in which

Fig. 1 is a perspective view of a stretcher embodying the invention in a preferred form;

Fig. 2 is a similar view of the stretcher in connection with the box toe raising device;

Fig. 3 is a similar view in connection with the vamp-seam-stretching device;

Fig. 4 shows the device of Fig. 2 in a shoe;

Fig. 5 shows the device of Fig. 3 in a shoe;

Fig. 6 is a sectional plan view taken from the top;

Fig. 7 is a vertical section on the line VII—VII of Fig. 6.

The fore part of the illustrated stretcher is split into two separable members 10, 10, each having, near its middle, a laterally extending cylindrical hole 14 located in an interior boss 16. A cylindrical plug or trunnion member 18 is rotatably mounted in each hole 14 and is held from slipping out by a screw 20 threaded into it and projecting into a longitudinally elongated hole 22 in the associated fore part member, the hole thus permitting the fore part member to rotate on the plug 18 around the transverse horizontal axis thereof. The front and rear ends of the hole serve as stops to limit this rotation.

Each plug is slotted at 24, and in the slot fore and rear links 26, 28 are pivotally mounted on the corresponding rear links 26, 28 are pivotally mounted on the corresponding pin 20. The boss 16 is slotted at 30 to receive these links and the slot is of ample width to permit the rotation of the fore part member on the plug 18. The two fore links 26 are pivotally mounted on a pin 32 in a slot 34 in a member 36, which is internally right-hand threaded to accommodate a right-hand threaded rod or operating member 38. The rod 38 is internally left-hand threaded with the same pitch as its outside right-hand thread, to take a left-hand threaded rod 40 having a slotted head 42. The rear links 28 are pivotally mounted on a pin 44 in the slotted head.

The links and the members 36, 38, 40 con-

stitute an operating mechanism for the fore part. If the rod 38 be rotated one turn right-handedly, the member 34 and pin 32 will be pulled toward the rod 38 by an amount equal to the pitch of the screws, while the screw 40 and pin 44 will be pushed away from the rod by the same amount. Thus, if the rod 38 be regarded as fixed in position the pins 32, 42 will approach each other at the same speed when the rod 38 is rotated to the right, and the parallelogram of links 26—28 will shorten longitudinally, pushing out the pins 20 and expanding the stretcher fore part. Owing to the equal pitch of the right and left screws, the pins 20 will always remain in the same position longitudinally, relatively to the rod 38. Thus the point at which pressure is applied through the fore part members is longitudinally fixed relatively to the operating rod 38. The rod 38 and its attached links, and the fore part members 10 can, however, swing relatively to each other about a horizontal axis transverse to the fore part members by virtue of the mounting 16—18, thus facilitating the insertion and use of the stretcher into a shoe irrespective of its height of counter.

The rod 38 is operated by a handle 46 on its outer end on a reduced portion 47 which begins at a shoulder or collar 48. Mounted on the reduced portion 47 is a freely rotatable sleeve 50 having a handle 52 and an external coarse thread to accommodate a similarly threaded heel piece or abutment 54. Turning the handle 52 will screw the abutment 54 along the sleeve and regulate its minimum distance from the fore part members 10.

In the use of the device as an ordinary stretcher, the fore part members are placed in the shoe and the abutment 54 is screwed back against the counter of the shoe to the proper distance from the fore part members to place them at that part of the shoe which it is desired to stretch. The operation of the handle 46 will then turn the rod 38 to spread the fore part members, as above described. The fore part members and plugs 18 swivel freely about the vertical axes of the pins 20 and about the transverse horizontal axis of the trunnion plugs 16, thus adjusting themselves freely to the shape of the shoe and preventing overstretching of portions adjacent to the tight portion, while the pins 20 remain at the same distance from the heel end of the shoe as the fore part members are spread, thus preserving the initial adjustment of the stretcher.

The invention also provides two devices for special purposes. The first to be described is a toe box raising attachment 56 (Figs. 2 and 4). This may have any desired external shape, corresponding to the shape of the shoes in which it is to be used and is hollow, as shown in Fig. 2, to adapt it to be slipped over the closed fore part of the stretcher.

The apparatus so assembled is placed in the shoe as before described, and the fore part with the box raising tool is pushed forward by means of the members 47—50—54, the fore part of the stretcher not being expanded. The member 56 is thus wedged under the toe box of the shoe and raises it into its normal position. This procedure is illustrated in Fig. 4. It will be obvious that this same procedure, with or without the tool 56, can be used to stretch the length of the shoe without affecting its width.

The other device above mentioned, which may be used alternatively, is a vamp-seam-stretching attachment 58 (Figs. 3 and 5). This device is also hollow to adapt it to be slipped over the closed fore part of the stretcher, but the attachment 58 is larger than the box raising tool 56, its perimeter increases rapidly toward the rear, and it is open at the front end to permit it to ride farther up on the fore part so that it may be positioned around the ball and just behind the toe box and under the vamp of a shoe into which the fore part of the stretcher is inserted. It is designed to be used in the same way as the device 56, with the stretcher fore part closed, the handle 52 alone being operated to force the stretcher forward in the shoe.

The appliances 56 and 58 are both constructed entirely to surround the fore part of the stretcher. Thus they can not slip out of place when the stretcher is forced into the shoe and their smooth, continuous bottom surfaces slip over the insole of the shoe without catching or scarring.

Having described my invention, what I claim as new and desire to secure by Letters Patent of the United States is:

1. In a shoe stretcher, a pair of separable fore part members, an operating mechanism constructed and arranged to separate the fore part members, each of said fore part members being pivotally connected to the operating mechanism solely at a point substantially distant from its ends in such manner as to permit free movement about a vertical axis and the operating mechanism being arranged to preserve unchanged the longitudinal location of the said intermediate pivoted points relatively to the operating mechanism as the mechanism is operated to separate the fore part members.

2. In a shoe stretcher, a pair of separable fore part members, an operating mechanism constructed and arranged to separate the fore part members, the fore part members being pivotally connected to the operating mechanism on a transverse horizontal axis whereby the operating mechanism may swing in a vertical plane relatively to the fore part members and the operating mechanism being arranged to preserve unchanged the location, longitudinally of the operating

mechanism, of the pivotal connections of the fore part members as the operating mechanism is operated to separate the fore part members.

- 5 3. In a shoe stretcher, an operating mechanism, a heel member adjustably mounted thereon, a pair of relatively expansible fore part members pivotally connected to the operating mechanism at points between their 10 ends, and means for moving the said points of pivotal connection laterally of the operating mechanism to spread the fore part members while preserving their distance from the heel member unchanged.
- 15 4. In a shoe stretcher, an operating rod, two pairs of links, arranged one pair on each side of the rod, the links of each pair having pivotally connected ends, a fore part member connected to each pair of links at 20 their junction in such manner as to permit free movement about a vertical axis, pivots connecting the other ends of one pair of links to the other ends of the other pair, and means for moving the last two said pivots 25 in opposite directions and at equal rates relatively to the rod.
5. In a shoe stretcher, a member threaded internally and externally with right and left-hand threads, respectively, second and 30 third threaded members engaging the said internal and external threads respectively, two pairs of links, each pair having ends pivotally mounted on each of the second and third threaded members, and a pair of 35 fore part members each pivotally connected to a link of each of the said pairs.
6. In a shoe stretcher, a member internally and externally threaded with right and left-hand threads, respectively, second and third 40 threaded members engaging the said internal and external threads respectively, two pairs of links, the pairs having ends pivotally mounted on the second and third threaded members respectively, a pair of trunnion 45 members each pivotally connected to a link of each of the said pairs, and a pair of fore part members one mounted on each trunnion member.
7. In a shoe stretcher, an opposite internally and externally threaded member, second and third threaded members engaging the 50 said internal and external threads respectively, two pairs of links, the pairs having ends pivotally and terminally mounted on the second and third members respectively, a pair of coaxial cylindrical members, each pivoted to a link of each of the said pairs, and a fore part member pivotally mounted on each cylindrical member.
8. In a shoe stretcher, an internally threaded slotted member, two links pivotally mounted at an end of each in the slot thereof, an 55 externally threaded rod arranged to be screwed into the threaded slotted member, said rod being also internally threaded op-

positely to but with the same pitch as its outside thread, a third externally threaded member arranged to be screwed into the threaded rod, a slotted head on the last named threaded member, a second pair of links pivotally mounted at an end of each in the slot of the head, two slotted cylindrical coaxial trunnion members with their axes transversely horizontal, the other ends of the two pairs of links being pivoted in pairs in the slots in the trunnion members respectively, and two fore part members, one pivotally mounted on each trunnion member.

9. In combination with a shoe stretcher having a fore part and means for forcing it into a shoe, a sleeve arranged to be slipped over the toe of the fore part of the stretcher and to surround completely a transverse cross-section of the fore part and to be pushed into a shoe by the fore part to shape the shoe.

10. In combination with a shoe stretcher having a fore part and means for forcing it into a shoe, a hollow frusto-conical attachment arranged to be slipped over the toe of the fore part and up to the instep portion thereof to stretch the shoe when driven into it by the fore part, the perimeter of the attachment increasing rapidly toward its rear end, whereby its stretching action will be concentrated on the neighborhood of the vamp seam of the shoe.

11. A shoe stretcher comprising a fore part, a heel member and means for separating them, and a member arranged to be slipped over the toe of the fore part, to be carried forward in a shoe thereby and to surround a transverse cross-section thereof completely, to enlarge the effective cross-section of the stretcher.

In testimony whereof I have signed my name to this specification.
